REFINING MINERAL OILS

Herbert G. M. Fischer, Westfield, N. J., assignor
to Standard Oil Development Company, a cor-
poration of Delaware

Application March 22, 1941, Serial No. 384,677

5 Claims. (Cl. 196—33)

The present invention is concerned with the refining of mineral oils. The invention is more particularly concerned with the removal of objectionable sulfur compounds, as for example, mercaptans from petroleum oils, especially from those petroleum oils boiling in the motor fuel boiling range. In accordance with the present process, objectionable mercaptan compounds are removed from petroleum oils containing the same by treating these mercaptan-containing oils with a spent deleaded doctor solution. Preferred modifications of the present invention comprise desulfurization operations for the removal of mercaptans utilizing a doctor solution in particular sequence and arrangement of stages.

It is known in the art to treat mercaptan-containing mineral oils, particularly mercaptan-containing petroleum oils boiling in the motor fuel boiling range by various procedures in order to remove the mercaptan compounds or to convert them into less objectionable disulfides. This is necessary since mercaptan constituents render the oil malodorous and undesirable. The usual method employed in the treatment of petroleum oils for the removal of mercaptan compounds, particularly for the treatment of petroleum oils boiling in the motor fuel boiling range, is to contact the oil under suitable conditions with a so-called, "doctor solution," comprising an alkaline sodium plumbeite solution. This sodium plumbeite solution is generally prepared by dissolving lead oxide in an excess of sodium hydroxide. When the petroleum oil and plumbeite solution are mixed, a chemical reaction occurs in which the mercaptans react with the sodium plumbeite to form oil-soluble lead mercaptides. These mercaptides are decomposed usually by the addition of free sulfur, resulting in the lead being precipitated as an insoluble lead sulfide and in the formation of disulfide compounds. This operation, known as "sweetening" may be summarized by the following reactions:

In this operation, in order to secure a high quality product it is very desirable that the soluble lead compounds be entirely removed. This may readily be accomplished by proper control of reagents, time and temperature but generally by the addition of a slight excess of free sulfur. However, the use of excess free sulfur even in relatively small quantities is not desirable since it increases the corrosive or polysulfide sulfur

content of the treated motor fuel and furthermore impairs the susceptibility of the motor fuel toward knock-suppressing agents, as for example, tetraethyl lead.

5 I have now discovered a process by which it is possible to employ a relatively small amount of doctor solution per volume of oil treated and to remove substantially completely the mercaptan compounds. My process secures a greater sulfur reduction per volume of doctor solution used than could heretofore be secured by using the conventional sweetening operation. In accordance with my process, mercaptan compounds are removed from feed oils containing the same by utilizing a spent doctor solution from which precipitated lead sulfide, preferably from which the entire amount of lead has been removed. My invention may be readily understood by reference to the drawing illustrating an embodiment of the same.

Referring specifically to the drawing the mercaptan-containing feed oil is introduced into initial treating zone 25 by means of line 26. In treating zone 25 the oil is contacted with a spent doctor solution which is introduced by means of line 27, which solution is substantially free of lead and is secured in a manner as hereinafter described. The mixture comprising the feed oil and the lead-free spent doctor solution is withdrawn from treating zone 25 by means of line 28 and passed to settling zone 29 wherein a separation is made between the spent doctor solution and the oil. The spent doctor solution is withdrawn from settling zone 29 by means of line 30 and at least a portion of the same withdrawn from the system by means of line 31 and disposed of in any manner desirable. This is necessary to maintain the system in balance. The remainder of the spent doctor solution is introduced into zone 32 wherein it is treated for the removal of objectionable sulfur compounds which are removed overhead by means of line 33. This is preferably secured by introducing steam by means of line 34. The treated spent doctor solution is withdrawn from zone 32 by means of line 35 and passed to spent doctor storage 36 from where it is recycled to treating zone 25 along with additional lead-free spent doctor solution which is introduced into zone 36 by means of line 37 and which is produced in a manner as hereinafter described. The treated oil separated in settling zone 29 is removed by means of line 38 and introduced into secondary treating zone 39 wherein it is contacted with doctor solution 55 which is introduced by means of line 40. Oper-

ating conditions are adjusted to secure substantially complete conversion of the mercaptan compounds in the oil. The treated oil is withdrawn from secondary treating zone 39 by means of line 41, mixed with sulfur which is introduced by means of line 53, and then passed into settling zone 42 wherein a separation is made between the treated oil and the spent doctor solution. The treated oil substantially completely free of mercaptan compounds is withdrawn from settling zone 42 by means of line 43 and handled in any manner desirable.

The spent doctor solution is withdrawn from settling zone 42 by means of line 44 and an appreciable proportion of the same passed into regeneration zone 45 wherein the same is treated after adding lead sulfide from line 51, preferably with an oxygen-containing gas which is introduced by means of line 46 in order to regenerate the doctor solution. The regenerated doctor solution is withdrawn from zone 45 by means of line 47 and passed to doctor storage 48 from where it is recycled to secondary treating zone 39 along with a fresh doctor solution which is introduced by means of line 49.

A portion of the spent doctor solution removed from settling zone 42 by means of line 44 is passed through filtering zone 50 wherein the precipitated lead sulfide is separated and removed by means of line 51. The spent doctor solution free of precipitated lead sulfide is removed from filtering zone 50 by means of line 52 and passed into tertiary treating zone 54 in which the doctor solution contacts a segregated portion of the feed oil which is introduced by means of line 55 under conditions completely to free the spent doctor solution of lead. The mixture is withdrawn from tertiary treating zone 54 by means of line 56 and introduced into settling zone 57 wherein a separation is made between the lead-free spent doctor solution and the oil. The oil containing dissolved therein soluble lead mercaptides is removed from settling zone 57 by means of line 58 and passed to secondary treating zone 39. The lead-free spent doctor solution is withdrawn from settling zone 57 by means of line 37, passed to spent doctor storage 36, and passed to initial treating zone 25 along with recycled spent doctor solution as described above.

The process of the present invention may be widely varied. It is to be understood that the respective zones may comprise any suitable number and arrangement of units. The character of the fresh doctor solution employed may be prepared in the conventional manner in which sufficient lead oxide is added to saturate a sodium hydroxide solution, preferably of from about 12° to about 20° Baumé. The quantity of fresh doctor solution employed per volume of oil may vary widely and will depend upon the character of the oil as well as upon other operating conditions. A sufficient amount should be used so as to completely convert the objectionable mercaptan compounds to the innocuous disulfide compounds. A sufficient amount of the oil is used for contacting the lead sulfide free spent doctor solution so that the doctor solution is substantially completely freed of lead.

In doctor sweetening operations, in which the spent doctor solution is regenerated by oxidation, thiosulfates and other similar salts are produced resulting in a corresponding reduction in the sodium hydroxide content. Therefore, in order to maintain the effectiveness of the doctor solution, it is necessary that the sodium hydroxide

content be kept above a certain minimum such as above about one pound of sodium hydroxide per gallon and that the content of thiosulfates and other salts be kept below a certain maximum, such as below about 1.5 pound per gallon. In order to stay within these limits, it is necessary to discard spent doctor solution and replace it with fresh doctor solution. In accordance with my invention, this spent doctor solution normally discarded is handled in a particular manner with respect to the feed oil being desulfurized, by which unexpected desirable results are secured.

It has been found that the spent doctor solution free of dissolved lead which is normally an objectionable waste product, can be satisfactorily and effectively used in accordance with my invention for the removal of mercaptans from feed oils. The spent doctor solution has been found to be several times as effective as an equal amount of fresh sodium hydroxide solution of equal concentration. This is evident from the results presented in the tables following:

Single stage extraction at 75° F. of a petroleum oil boiling in the heavy naphtha boiling range and containing 35 mg. of mercaptan sulfur per 100 cc. oil utilizing 10% by volume of a sodium hydroxide solution and a spent doctor solution respectively

30		Pure NaOH solution			Spent doctor solution		
		.65	1.15	1.34	.65	1.15	1.34
	Extracting solution: NaOH content, #/gal.....	.65	1.15	1.34	.65	1.15	1.34
	Treated pet. oil:	26	24	22	24	7	4
35	Mg. mercaptan S/100 cc.....	26	31	37	31	80	89
	Per cent mercaptan removed.....						

Single stage extraction at 75° F. of a petroleum oil boiling in the heavy naphtha boiling range utilizing 20% by volume of a sodium hydroxide solution and a spent doctor solution respectively

45		Pure NaOH solution			Spent doctor solution		
		.65	1.15	1.34	.65	1.15	1.34
	Extracting solution: NaOH content, #/gal.....	.65	1.15	1.34	.65	1.15	1.34
	Treated pet. oil:	22	20	19	20	3	1
50	Mg. mercaptan S/100 cc.....	37	43	46	43	91	97
	Per cent mercaptan removed.....						

The results obtained by extracting the sour naphtha with 10 or more percent of spent doctor solution containing 1.15 pound or more of NaOH per gallon in a single-stage operation are of particular interest. These procedures removed 80% or more of the mercaptans present in the naphtha. The use of two or more stages of countercurrent extraction in any of these cases results in the production of a sweet naphtha. The extraction of this naphtha with pure sodium hydroxide of similar concentrations and quantities resulted in the removal of only 31 to 46% of the mercaptans. In this case an extremely large quantity of pure sodium hydroxide and a multi-stage countercurrent extraction system are required to obtain a sweet naphtha.

In extracting mercaptans with spent doctor solution, the effectiveness of the extraction decreases as the mercaptan content of the solution increases. However, the mercaptans can readily be recovered and the solution regenerated to its original effectiveness by steam distillation at atmospheric pressure or at elevated pressures.

What I claim as new and wish to protect by Letters Patent is:

1. In a process for the removal of mercaptan compounds from a petroleum oil containing the same, the improvement which comprises removing lead from a spent doctor solution and contacting the oil with the resulting solution whereby the mercaptan compounds are removed.

2. Process for the removal of mercaptan compounds from a petroleum feed oil, the improvement which comprises contacting the oil in an initial treating zone with a spent doctor solution free of lead, separating the treated oil and spent doctor solution in a settling zone, and recycling at least a portion of the spent doctor solution to said initial treating zone, contacting the treated oil removed from said initial treating zone in a secondary treating zone with a fresh doctor solution, separating the treated oil and the spent doctor solution and segregating a portion of the spent doctor solution, removing the lead from the segregated portion and recycling the deleaded spent doctor solution to the initial treating zone.

3. Process as defined by claim 2, in which said petroleum oil boils in the motor fuel boiling range.

4. Process as defined by claim 2, in which the segregated portion of the spent doctor solution is freed of lead by filtering the lead sulfide and contacting the filtered spent doctor solution with a segregated portion of fresh feed oil in a tertiary treating zone under conditions to convert the lead plumbite into oil-soluble lead mercaptides, 10 and under conditions in which the segregated portion of the feed oil containing said soluble lead mercaptides is passed to said secondary treating zone.

5. Process as defined by claim 2, in which the 15 remaining portion of the spent doctor solution which has not been deleaded is passed to a regeneration zone wherein it is treated with an oxygen-containing gas under conditions to regenerate the doctor solution, recycling said regenerated doctor solution to said secondary treating zone.
